DESIGN FOR A SHOE

Mabel Winkel and Charles A. Julianelli,
New York, N. Y.

Application March 8, 1939, Serial No. 83,425

Term of patent 3½ years

To all whom it may concern:

Be it known that we, Mabel Winkel and Charles A. Julianelli, citizens of the United States and residents of the city, county, and State of New York, have invented a new, original, and ornamental Design for Shoes, of which the following is a specification, reference being had to the accompanying drawing, forming a part thereof, in which

Fig. 1 is a side elevation of a shoe, showing the new design, and

Fig. 2 is a plan view of the same.

We claim:

The ornamental design for a shoe, as shown.

MABEL WINKEL.
CHARLES A. JULIANELLI.
